LEAF SPRING

Donald Russell Martin Yates, Highclere, Chislehurst, England

Application January 30, 1937, Serial No. 123,311
In Great Britain February 3, 1936

2 Claims. (Cl. 267—52)

This invention relates to leaf springs such as are commonly employed in the suspension of locomotives, railway, road and like vehicles and/or wagons.

5 In existing springs the various leaves are interconnected according to common practice by nibbling, so as to prevent relative sideways movement between the individual leaves, and in order to suspend the spring in correct position a buckle 10 or strap is applied by a shrinkage process. In course of time, the individual leaves may wear or break and it becomes necessary to strip the spring, that is to say, to disperse the various leaves. During the process of stripping it is 15 sometimes found that as many as 60% of the buckles are cracked owing to excessive strains of shrinking on or pressing off.

The object of the present invention is to provide 20 a means of assembly of the individual leaves of the spring so that they can readily be stripped in such a manner as to minimize or nullify the possibility of cracking of the spring buckles or straps.

According to the present invention the leaves constituting the spring are embraced by a strap 25 or buckle between which and the outside or top leaf of the spring is positioned one or more wedge shaped members whereby compression on the leaves can be adjusted.

Preferably two wedge shaped members are 30 provided the adjustment of the compression on the leaves being obtained by means of tightening a U bolt which is adapted to pass through the strap or buckle and so exert a force on one of the wedge shaped members.

35 The invention is illustrated in the accompanying drawing in which:

Figure 1 is a side elevation,

Figure 2 a section on the line 2—2 Figure 1 and

40 Figure 3 a section on the line 3—3 Figure 1.

In the drawing, the leaves 1 of the spring are embraced by a strap or buckle 2 which as shown at the top is doubled upon itself and welded. A U-bolt 3 passes through a space between the 45 undersurface of the top of the strap and the top leaf of the spring. The limbs of the U-bolt pass through holes in a block 4 and embrace means for varying the compression on the leaves of the spring. The said means comprises two 50 wedge shaped members 5, 6, the horizontal part 3'

of the U-bolt acting upon the wedge 5 to draw it towards the block 4, the block 4 tending to force the wedge member 6 in the reverse direction.

When it is desired to strip the spring, all that 5 is necessary is to slacken nuts 7 on the limbs of the U-bolt and hence allow the wedge shaped members to have relative movement whereby the compression on the leaves constituting the spring is reduced so that the individual leaves can readily 10 be dispersed whereby the risk of cracking the buckle or strap is nullified or minimized.

Such an arrangement may be employed with the usual method of assembly in the buckle or strap, i. e. the shrinkage process or again it may 15 advantageously be employed with the cold assembly process and buckle device described in my co-pending application No. 3278/36 in Great Britain.

What I claim is:—

1. A leaf spring for use in the suspension of 20 locomotives, railway, road and like vehicles and/or wagons in which there is provided a straplike member which embraces the leaves of the spring, two wedge shaped members positioned between the straplike member and the outside 25 leaf of the spring, a U-bolt which embraces said wedge members and passes through said straplike member, a block carried by said U-bolt and against which one of said wedge members abuts and means for tightening said U-bolt to cause 30 relative movement between said wedge members to adjust the compression on the leaves of the spring.

2. A leaf spring for use in the suspension of 35 locomotives, railway, road and like vehicles and/or wagons in which there is provided a straplike member which embraces the leaves of the spring, two wedge shaped members positioned between the straplike member and the outside leaf of the spring, a U-bolt which embraces said 40 wedge members and passes through said straplike member, the horizontal limb of the U-bolt abutting against one of said wedge members, a block carried by said U-bolt and against which the other wedge member abuts and means for tightening 45 said U-bolt to cause relative movement between said wedge members to adjust the compression on the leaves of the spring.
